UNITED STATES PATENT OFFICE.

EDGAR SCOFIELD, OF NEW YORK, N. Y., ASSIGNOR TO ANCHOR CAP AND CLOSURE CORPORATION, OF LONG ISLAND CITY, NEW YORK, A CORPORATION OF NEW YORK.

FRICTION CLOSURE CAP.

Application filed May 7, 1926. Serial No. 107,404.

The present invention relates broadly to packaging and more specially to a closure cap of the friction type.

The present invention comprises an improvement upon the type of friction closure cap illustrated in the Ramsey Patent No. 1,327,963, January 13, 1920.

Friction closures which have the retaining friction applied to substantially a cylindrical surface of glass jars, tumblers, or the like, are best held in position where the side friction is applied at a point sufficiently below the mouth of the container to bring the point of contact between the cap and the vessel below the part of the vessel formed by the ring mold.

The ring mold used upon the mouth of such vessels when the vessel is being made, is lifted vertically after the mouth has been pressed and this ring mold is provided with a sufficient clearance taper to permit the ring to be removed without injuring the ware. This produces an inclined surface adjacent the mouth of the container in the form of the frustum of a cone. Where friction in the nature of metal to glass contact is applied on this conical surface there is a tendency to cause the cap to wedge off of the vessel.

The present invention comprises a closure cap of the friction type with the line of contact between the cap and the container arranged to occur adjacent the lower portion of the cap. Furthermore, the stresses in the side wall of the cap where it bears on the containers are effective in such manner as to tend to resist the movement of the cap from the vessel.

Other and further objects of the present invention will in part be obvious and will in part be pointed out hereinafter in the specification following by reference to the accompanying drawings forming a part thereof.

Figure 1 is a sectional view through a cap in accordance with the present invention.

Figure 2 is an enlarged sectional view of a portion of the cap in position on the mouth of a suitable container.

Figure 3 is a diagrammatic view illustrating the forces tending to retain the cap in position on a substantially cylindrical side walled vessel.

Referring now more specially to the draw-

ings, the present invention comprises a closure cap having a cover portion 1 provided with a depending skirt 2 which terminates in a wire edge 4. The skirt of the cap is concave between the top and bottom thereof and is provided with indentations 5 which form frictional lugs that engage the surface of the glass container 6 to hold the cap in position thereon. The indentations or corrugations are constructed to cause the point of contact between the glass and the cap to occur as at 7 adjacent the wire edge 4.

It will be noted that the wire edge comprises a roll of the metal arranged in such manner that the skirt meets the wire edge in a line substantially coincident with a radii 70 of the coil. This arrangement causes the wire edge to very stiffly support the corrugations in the skirt.

The abrupt angle illustrated by the arrow A, Fig. 3, at which the bottom of the 75 skirt approaches the point of contact 7 causes this portion of the skirt to tightly grip the glass and because of the surface irregularities occurring in the glass similar irregularities in the metal of the cap act as ratchets 80 to resist the removal of the cap from the jar.

Having described my invention, I claim:

1. A closure cap having a cover portion and a skirt portion, said skirt portion having frictional engaging means provided therein, 85 said means comprising curved members having an abrupt curvature in the lower portion and a lesser curvature in the upper portion to provide the point of contact adjacent the lower edge of the skirt of the cap. 90

2. A closure cap having a cover portion and a skirt portion, said skirt portion having frictional engaging means provided therein, 95 said means comprising curved members having an abrupt curvature in the lower portion and a lesser curvature in the upper portion to provide the point of contact adjacent the lower edge of the skirt of the cap, and a wire edge at the lower edge of the cap to support the sealing forces. 100

3. A closure cap having a non-expansible cover portion and a skirt portion, said skirt portion having frictional engaging means provided therein, said means comprising curved members having an abrupt curvature 105 in the lower portion and a lesser curvature in the upper portion to provide the point of contact adjacent the lower edge of the

skirt of the cap, and a wire edge at the lower edge of the cap to support the sealing forces, said skirt meeting said wire edge on substantially a diameter of the cross section of said edge.

4. A closure cap comprising a cover portion; a skirt portion having frictional sealing means having a curved portion on a short radius leading to the lower edge of the skirt, and a curved portion on a greater radius leading to the upper edge of the skirt, whereby the sealing zone is below the central portion of said skirt.

5. A closure cap comprising a cover portion; a skirt portion having frictional sealing means having a curved portion on a relatively short radius leading to the lower edge of the skirt, and a curve on a longer

radius leading to the cover portion, and a wire edge on the lower edge of the skirt.

6. A closure cap comprising a cover portion, a depending skirt, an annular frictional sealing zone in said skirt, said zone comprising an abrupt curvature in its lower portion and a lesser curvature in the upper portion to provide a zone of contact adjacent the lower edge of the skirt of the cap.

7. A closure cap comprising a cover portion, a skirt, and frictional sealing means comprising corrugations extending transversely of said skirt and curved throughout their length, the portions of said curved sealing means adapted to contact with the side wall of the container being below the central portions thereof.

EDGAR SCOFIELD.
